C. P. DUBBS

PROCESS FOR CRACKING HYDROCARBON OIL

Filed Oct. 21, 1922

Patented July 27, 1926.

UNITED STATES PATENT OFFICE.

CARBON P. DUBBS, OF WILMETTE, ILLINOIS, ASSIGNOR TO THE UNIVERSAL OIL PRODUCTS COMPANY, OF CHICAGO, ILLINOIS, A CORPORATION OF SOUTH DAKOTA.

PROCESS FOR CRACKING HYDROCARBON OIL.

Application filed October 21, 1922. Serial No. 595,947.

This invention relates to improvements in a process for cracking hydrocarbon oils and refers more particularly to a process in which relatively high boiling point oils are converted into oils of lower boiling point, such as gasoline and the like.

Among the salient objects of the invention are:

10. To provide a process in which the oil is primarily raised to a cracking temperature in the heating zone and is then passed to a vaporizing chamber, from which the vapors evolved are passed through dephlegmating and condensing stages,
15. To provide a process in which the oil vaporized under pressure is passed through a dephlegmating stage and thence through stages of reduced pressure whereby subsequent to the first pressure dephlegmation 20 the oil is subjected to fractionation in successive stages under reduced pressure and the lighter products of the oil removed therefrom,

To provide a process whereby a high grade gasoline-like distillate may be obtained due to the subsequent fractionation under reduced or atmospheric pressure,

To provide a process in which these lighter products may be drawn off and collected or returned and re-cycled either through the heating stage or through the preceding dephlegmating stages.

The single figure is a diagrammatic side elevational view of the apparatus.

35. Referring to the drawings, the oil to be treated is introduced through the line 1, controlled by a valve 2, and is sprayed into the dephlegmator 3 at about midway of its height. This reduces the possibility of any 40 of the lighter fractions contained in the raw oil from being carried over with the heated vapors which are rising through the dephlegmator. A series of pans or perforated trays 4 are positioned in the dephlegmator 45 for interrupting the flow, both of the rising vapors and the down coming liquids. The raw oil after serving as a dephlegmating medium collects in the bottom leg 5 of the dephlegmator, from which it is drawn off 50 through a line 6 controlled by a valve 7, and thence passes through line 8 to the heating coils 9, which are positioned in the tube compartment of the furnace 11. This furnace is of the side-fired type, having a com-

bustion chamber 12 in which the heat is generated. The combustion gases pass through the duct 13 and circulate downwardly over the heating tubes and out through a flue not shown. The oil after being raised to a cracking temperature in the heating zone is passed to an expansion or vaporizing chamber 14 through the transfer line 15. This transfer line has interposed therein a valve 16 for control of the liquid and pressure conditions if desired.

The vaporizing chamber consists of an enlarged tank which is equipped with try-cocks 17 and a residuum draw-off line 18 controlled by a valve 19. The vapors evolved in the chamber 14 rise through the vapor line 20 in which is interposed the valve 21 and are introduced to the bottom of the dephlegmator 3 through which they rise and are subjected to the refluxing action of the incoming raw oil and returned distillate as will hereinafter be explained.

From the vapors is separated condensate which flows back with the raw oil for re-treatment in the heating tubes. The uncondensed portion of the vapors passes off through the line 22 controlled by the valve 23 and is introduced to the lower portion of a fractionating column 24. This fractionating column is similar in construction to the dephlegmator 3. The upward travel of the vapors is obstructed by perforated pans or trays as shown at 25.

Enclosing the fractionating column is a casing or shell 26 which is equipped with adjustable shutters 27 by means of which the temperature of the air surrounding the fractionating column may be controlled; that is, by opening the shutters, the circulation of the air is permitted about the column while if the shutters are closed or substantially closed the shell or housing will serve as an insulator and retain the heat of the column.

The vapors rising through the fractionating column 24 are subjected to the dephlegmating or refluxing action of a returned distillate formed by subsequent dephlegmation of the vapors. The liquid portion separated from the vapors in this fractionating column is drawn off through the line 28 controlled by valve 29 and is collected in the tank 30, from which it may be withdrawn through a valve 31 and passed to

storage or returned through the line 32, 48, pump 34 and line 35 to the line 8 communicating with the heating tubes.

An alternate method of handling this condensate is to close the valve 36 and withdraw the liquid through the line 37 and charge it through the pump 38 and line 39 to the top of the dephlegmating column 3. This condensate is charged to the dephlegmator near its top as it contains relatively refractory liquid and is not easily carried over in a vapor state by the reflux vapors passing off from the top of the dephlegmator.

15 In a similar manner, the vapors undischarged in the fractionating column 24 pass off through the line 40 in which is interposed a valve 41 and are introduced to the bottom of a second fractionating column 43, which is similar in design to the fractionating column 24. It is also surrounded by a shell or housing which has adjustable shutters for controlling the temperature of the column. In a like manner, the liquid material separated out in this column is drawn off through a line 44 controlled by a valve 45 and is collected in a tank 46, from which it may be similarly handled as the condensate separated out in the column 24; that is, it may be drawn off through a line 47 to storage, returned to the heating coils through a line 48 controlled by a valve 49 or recharged into the top of the fractionating column 24 by means of the pump 50 and return line 51, in which is interposed a control valve 52.

From the second stage of fractionation the vapors pass off through a line 53 to a final condensate stage, which consists of a condenser coil 54 housed in a water condenser box 55. The liquid products from this final condensing action pass down through the pipe 56 to the receiver 57. Valves 58 and 59 are interposed in the pipes 53 and 56 respectively. The receiver is equipped with a pressure relief valve 60, pressure gauge 61, liquid level gauge 62 and a draw-off valve 63. A second draw-off line 64 furnishes a means for re-cycling the distillate collected in the receiver by means of a pump 65 back to the fractionating column 43 through a pipe 66. Liquid level gauges 67 are positioned on the sides of the tanks 30 and 46 for ascertaining the level of the oil in the tanks and pressure gauges 68, 69 and 70 are tapped into the top of the dephlegmator 3 and fractionating columns 24 and 43 respectively.

In operating the process as explained, the oil, which may be of any character, which may be effectively and commercially cracked by heat and pressure, is charged into the dephlegmating stage and after serving as a refluxing medium, together with what reflux condensate it may collect therein, is passed

to the heating stage where it is raised to a conversion temperature ranging from 500° F. to 900° F., according to the character of the oil and the pressures imposed. The oil is then conducted to the vaporizing chamber where it is permitted to collect into a substantial body, the vapors rising through the vapor line to the dephlegmating stage while the liquid level in the chamber may be controlled by the residuum draw-off valve 19. The vapors, after being subjected to dephlegmation under pressure substantially the same as that maintained in the heating stage or at a differential pressure, if desired, somewhat lower than that in the heating or vaporizing stages, are passed over through the line 22 in which is interposed the reduction valve 23. Here the pressure on the vapors is reduced and they are directed through the successive stages of fractionation which takes place in the columns 24 and 43. In these columns the vapors, as stated, are at considerably lower pressure than the vapors in the initial stages of the system, or if desired, this fractionation may take place at atmospheric pressure. The conditions of operation will depend to a great extent upon the character of the distillate desired and the character of the oil being treated. The separate liquid products separated from the vapors in the columns 24, 43 and that collected in the final condenser 57 will consist of distillates of a relatively different character. That is, there will be separated out of the first column a condensate of a relatively higher boiling point than that separated out in the subsequent stages. The boiling points and gravities of the different condensates will vary with the character of the fractionating conditions. That is, the temperatures and pressures in the successive stages of fractionation and condensation will govern to a great extent the condensates and distillates obtained.

A further method of operation would be to maintain relatively higher pressures; that is, pressures ranging from 50 to 300 lbs. per square inch in the heating, vaporizing and initial dephlegmating stages and reducing the pressure in the first fractionating column from 25 to 50 lbs., and a second reduction to 10 or 15 lbs. or to atmospheric conditions in the secondary fractionating column 43.

A further reduction may be effected by the valve 58 if any pressure is maintained on the secondary column 43.

This process has the advantage that the pressure distillate vapors may be run directly through fractionating columns at reduced pressures, whereby distillates or condensates are obtained, which are substantially the same in character as would be obtained by subsequent distillation.

The character of the apparatus may be varied without departing from the spirit of the invention.

I claim as my invention:

5. 1. A process for cracking hydrocarbon oil consisting in raising the oil to a conversion temperature in a heating zone, collecting the heated oil in a substantial body in a vaporizing zone and causing the heating and vaporization to take place under substantial pressure of the evolved vapors, passing the vapors to a dephlegmating zone and there subjecting them to the refluxing action of the incoming raw oil, passing the unden- 60 densed vapors under reduced pressure conditions to successive fractionating zones, condensing and collecting the unden- 65 densed vapors passing over from the final zone, and returning selected portions of the condensate from each of the separate fractionating zones to the preceding fractionating zone.
2. A process for cracking hydrocarbon oil consisting in raising the oil to a conversion temperature in a heating zone, collecting the heated oil in a substantial body in a vaporizing zone and causing the heating and vaporization to take place under substantial pressure of the evolved vapors, passing the vapors to a dephlegmating zone, and there subjecting them to the refluxing action of the incoming raw oil, passing the unden- 70 densed vapors under reduced pressure conditions to successive fractionating zones, condensing and collecting the unden- 75 densed vapors passing over from the final zone, and returning selected portions of the condensate from each of the separate fractionating zones to the preceding fractionating zone.
3. A process for cracking hydrocarbon oil consisting in utilizing the charging stock as a dephlegmating medium, charging the oil thence to a heating stage and transferring the oil in a heated condition to a vaporizing zone and there maintaining it in a substantial body during vaporization, passing the evolved vapors to and through a dephlegmating zone and maintaining a substantial pressure upon the heating, vaporizing and dephlegmating zone, releasing the pressure subsequent to dephlegmation and passing the vapors under reduced pressure conditions through successive fractionating zones, con- 80 densing and collecting the vapors from the final zone, collecting the condensate from each of the separate fractionating zones and returning selected portions to the preceding zone and recycling portions to the heating zone for retreatment.
4. A process for cracking hydrocarbon oil, consisting in raising the oil to a conversion temperature in a heating zone, passing the heated oil to an enlarged zone where vaporization occurs, in cooling the evolved vapors by passing the same to a primary dephlegmating zone, in maintaining a super-atmospheric pressure on the oil undergoing conversion and on the vapors passing through the dephlegmating zone, in subjecting such vapors in the primary dephlegmating zone to the refluxing action of charging oil passing in heat conductive relation with said vapors, in discharging unden- 85 densed vapors from the primary dephlegmating zone to a succeeding zone maintained under a pressure lower than the pressure maintained in the primary dephlegmating zone and where further fractionation occurs, in returning portions of the condensate produced in said succeeding zone to the preceding primary dephlegmating zone, and in discharging from said succeeding fractionating zone unden- 90 densed gasoline-like vapors for further condensation and collection.
5. A process for cracking hydrocarbon oil, consisting in raising the oil to a conversion temperature in a heating zone, passing the heated oil to an enlarged zone where vaporization occurs, cooling the evolved vapors by passing the same to a primary dephlegmating zone, in maintaining a super-atmospheric pressure on the oil undergoing conversion and on the vapors passing through the dephlegmating zone, in discharging unden- 95 densed vapors from the primary dephlegmating zone to a succeeding zone maintained under a pressure lower than the pressure maintained in the primary dephlegmating zone and where further fractionation occurs, in returning portions of the condensate produced in said succeeding zone to the preceding dephlegmating zone, and in discharging from said succeeding fractionating zone gasoline-like unden- 100 densed vapors for further condensation and collection.
